UNITED STATES PATENT OFFICE.

ERNST MESEKE, OF CHICAGO, ILLINOIS.

LOCOMOTIVE JOURNAL-BOX.

SPECIFICATION forming part of Letters Patent No. 394,988, dated December 25, 1888.

Application filed July 13, 1888. Serial No. 279,860. (No model.)

To all whom it may concern:

Be it known that I, ERNST MESEKE, of Chicago, in the county of Cook and State of Illinois, have invented certain new and useful 5 Improvements in a Locomotive Journal-Box, of which the following is a full, clear, and exact description, that will enable others to make and use the same, reference being had to the accompanying drawings, forming a part of 10 this specification.

The object of this invention is to provide a means for compensating for the wear of the upper brass or bearing and keeping the space formed underneath the axle by reason of such 15 wear closed up, thus excluding dust and dirt and preventing the lubricating material from working out.

Figure 1 is a vertical transverse section in plane 1, Fig. 2. Fig. 2 is a vertical longitudinal section in plane 2, Fig. 1; Fig. 3, an elevation of the inner end; Fig. 4, an elevation of the outer end next the truck-wheels, and Fig. 5 a sectional detail of construction.

Referring to the drawings, A A represent 25 the axle-box frame; B, the oil-box; C, the axle, and D the journal-brass. The inner sides of the box-frame is provided with a number of horizontal rectangular grooves, a, the oil-box B having corresponding edges, a', 30 which engage with said grooves, whereby said oil-box is removably retained in place. The box-frame A may be attached to the engine-frame in any suitable manner, the transverse clamping-rod a² serving to lock the oil-box 35 and box-frame firmly together.

The inner end of the oil-box is provided with the downwardly-projecting part E, having the chamber a³, in which is inserted the slide or plate a⁴, adapted to have a vertical adjustment therein. The bolts a⁵ serve to retain 40 the slide at any point to which it may be set.

The lug a⁶ on the slide provides a means 45 whereby the same may be raised upward closely against the under side of the axle, so as to keep the space usually formed by the gradual wearing away of the brass closed up, and thereby excluding the dust and dirt from the oil-chamber, and at the same time preventing the cotton waste or other oil absorb- 50 ent that may be used from working out.

A companion slide, b, is placed inside of and

at the opposite end of the oil-box. This slide conforms to the shape of the box, and when at its lowest position rests upon the bottom of the inclosing-box instead of passing below the 55 same, as does the space-closing slide at the opposite end. The slide b is adjustably secured in place by means of two headless screw-bolts, b' b². (See Figs. 1, 4, and 5.) The outer ends of these bolts are of a greater diameter 60 than the inner ends, and have a left-handed screw-threaded engagement in the end of the oil-box, so that they pass inward when turned to the left. The opposite or inner ends of these bolts have a right-handed screw-thread and 65 engage with the clamping-nuts b³ b⁴, bearing against the inner side of the slide b, as shown in Figs. 1 and 5. Now, when these bolts are turned to the left, the clamping-nuts are moved away from contact with the slide b, so that 70 the same may be raised or lowered as required, and when turned in the opposite direction the slide is clamped in place. The outer ends of these bolts do not project beyond the surface 75 in which they are inserted, and are provided with the slots b⁵ for the reception of the point of a screw-driver or other suitable instrument for turning said bolts. One-half a turn of the bolts in either direction is all that is required. The necessity for this peculiar construction 80 and arrangement arises from the fact that there is but little room or space between this end of the journal-box and the truck-wheels. 85

The slide b is provided with elongated slots d where the bolts b' b² pass through, to permit 85 of a free vertical movement. d' is a strip of leather inserted between the end of the journal and oil box and the slide b, so as to provide a firm holding ground and prevent the slide from being shifted by the jar of the engine, as it is not possible to set up the bolts as 90 tight at this end as at the other, where there is more room.

The upper edges of the companion slides are cut away on a circle to conform to the 95 contour of the axle. The inner end of the oil-box is cut away to a greater depth than at the opposite end, for the reason that the cotton waste is inserted and removed at this point, the projecting part E providing for the 100 use of a longer slide, as shown in Fig. 3.

Having thus described my invention, what

I claim as new, and desire to secure by Letters Patent, is—

1. In a locomotive journal-box, the combination, with the axle-box provided with rectangular grooves, as described, of the oil-box B, having corresponding edges engaging with said grooves and provided with the downwardly-projecting and chambered part E, the clamping or locking rod locking said parts together, the vertically-adjustable slide a^1 , and the means described for retaining said slide in the position to which it is adjusted, substantially as and for the purpose set forth.

2. The combination, with the oil-box and the truck-axle, of the adjustable slide b , the

headless right and left screw-threaded bolts $b' b^2$, and the clamping-nuts $b^3 b^4$, substantially as and for the purpose set forth.

3. In a locomotive journal and oil box, the combination of the oil-box and truck-axle with the vertically-adjustable companion slides located at each end of said oil-box, and the means described for retaining said slides in the position to which they have been adjusted, substantially as and for the purpose set forth.

ERNST MESEKE.
